UNITED STATES PATENT OFFICE.

REUEL B. FRANKLIN, OF FORT MADISON, IOWA.

KAFIR-CORN HEADER.

SPECIFICATION forming part of Letters Patent No. 669,688, dated March 12, 1901.

Application filed June 27, 1900. Serial No. 21,707. (No model.)

To all whom it may concern:

Be it known that I, REUEL B. FRANKLIN, a citizen of the United States, residing at Fort Madison, in the county of Lee and State of Iowa, have invented certain new and useful Improvements in Kafir - Corn Headers, of which the following is a specification.

This invention relates to improvements in a machine to be used for cutting off and gathering the heads of Kafir corn; and it consists in certain peculiarities of the construction, novel arrangement, and operation of the various parts thereof, as will be hereinafter more fully set forth and specifically claimed.

15 One object of this invention is to provide a simple, inexpensive, and effective machine for cutting off, collecting, and transporting the heads of Kafir corn or similar growths in such a manner that the stalks, with the fodder thereon, may be left standing in order that the latter may be gathered at a later time.

Another object of the invention is to so construct the machine that it may be tilted so as 25 to accommodate stalks of different heights—that is to say, that the cutter-bar may be tilted to the proper position to cut the stalks just below the heads whatever may be the height of the stalks.

30 Other objects and advantages will be disclosed in the subjoined statement.

In order to enable others skilled in the art to which my invention pertains to make and use the same, I will now proceed to describe 35 it, referring to the accompanying drawings, in which—

Figure 1 is a view in side elevation of the machine. Fig. 2 is a plan view thereof; and Fig. 3 is a vertical transverse sectional view, 40 taken on line 3 3 of Fig. 2, looking in the direction indicated by the arrows.

Similar letters refer to like parts throughout the different views of the drawings.

45 A and A' represent the collecting boxes or receptacles for the heads after they have been severed from the stalks. These receptacles are preferably rectangular in shape, as shown, and have their upper ends open and their lower portions provided with inclined 50 floors a to cause the heads to slide outwardly therefrom when the doors a', which are hinged to the upper portion of said receptacles, are

opened, as shown by dotted lines in Fig. 3 of the drawings. Each of the boxes is provided on its lower portion, about the middle of the 55 side thereof, with a socket a² to receive a bolt a³, located on the outside of each of the doors and which bolts and sockets are employed to fasten the doors in their closed positions. Secured to the upper end of each of the bolts 60 a³ is a wire or cord a⁴, which has at its upper end a handpiece a⁵, movably secured to the upper portion of the boxes and employed for disengaging the bolts from their respective sockets. The boxes or receptacles A 65 and A' are pivotally mounted on shafts B, on which are the traction-wheels B', which revolve in suitable depressions or wheel-boxes a⁶, formed in the lower part of the collecting-receptacles. These receptacles are held a 70 slight distance apart in order to stride the row of corn by means of a frame C, composed of uprights c, which supports the gathering and cutting mechanism. Extending from the inner surface of the upper portion of one of 75 the boxes to the like portion and surface of the other box is an arched roof or covering A², on which the heads of corn will fall after being cut from the stalk and from which they will pass into the boxes. Secured horizontally 80 to each side of the frame C is a cross-piece c', on the front and rear end of which is journaled a sprocket-wheel c² and c³, respectively, around which pass sprocket-chains C', each of which is provided with fingers c⁴ to engage the heads 85 of the corn and to force the stalks backwardly over the cutter-bar. Vertically journaled on each side of the frame C are shafts D and D', which are provided on their lower ends with beveled gears d, which mesh with similar gears 90 d' on the auxiliary shafts B², which are journaled on the front portion of each of the collecting-receptacles. Mounted on the upper end of each of the shafts D and D' is a sprocket-wheel c⁵, which engages and drives the chains 95 C', carrying the fingers. On each of the shafts B² is a sprocket-wheel d², and on each of the shafts B is a sprocket-wheel d³, over which and the sprocket-wheels d² pass sprocket-chains d⁴, used for driving the gathering and 100 cutting mechanism. On one of the shafts B² is mounted an eccentric E, to which is secured the lower end of a rod E', the other end of which is pivotally secured to one arm of a

bell-crank lever F, which is fulcrumed on a suitable support G, secured to the frame C and usually at the rear thereof. To the other arm of the bell-crank lever F is pivoted at 5 one of its ends a bar g, the other end of which is pivotally secured to the cutter-bar H, which is horizontally and transversely supported at the rear of the frame C by means of cross-pieces c⁶, secured to said frame.

10 The cutter-bar may be of the ordinary or any preferred construction. Journaled on the rear ends of the pieces c⁶ is a rock-shaft I, the ends of which are bent downwardly and have pivotally secured thereto rods or bars L, 15 the other ends of which are similarly secured to the poles or tongues M, which are pivotally secured at their rear ends to the boxes A and A' and may have at their front ends suitable means (not shown) for connecting them to 20 horses which draw the machine. Fulcrumed at its lower end to one of the collecting boxes or receptacles is a lever N, which is pivotally connected, by means of a link n, to one end of the rock-shaft. The rear portion of the 25 boxes or collecting-receptacles is provided with a support O for the seat P, on which the driver may sit.

From the foregoing and by reference to the drawings it will be seen and readily under-

30 stood that the machine is so mounted on the shafts B that the weight of the driver will about counterbalance the weight of the collecting and cutting mechanism. By driving the horses, which may be hitched to the front 35 ends of the boxes or collecting-receptacles by means of singletrees R or otherwise, so that the machine will stride the stalks or corn to be operated on it is evident that the heads thereof will be drawn together and backwardly over the cutter-bar, when the same 40 will be cut off thereby, after which they will fall on the roof or cover A² and from there into the boxes, from which they may be emptied when the end of the row is reached by 45 raising the doors a' at the outside of the boxes. By pressing the lever N forwardly the machine will be tilted so that the cutter-bar and fingers c⁴ will reach just below the heads of the taller stalks, when by retracting the lever 50 the machine may be raised so as to cut the heads of the lower stalks.

Having thus fully described my invention, what I claim as new, and desire to secure by Letters Patent, is—

55 1. The combination of two collecting-receptacles pivotally mounted on traction-wheels, with a piece inclined toward each of the receptacles and uniting their upper inner portions, a gathering mechanism and a cutter-bar 60 mounted above the front portion of the said re-

ceptacles, suitable gearing and connections between the shafts of the said wheels and the gathering mechanism and cutter-bar, whereby the same are operated by the revolution of the traction-wheels, substantially as 65 described.

2. The combination of two collecting-receptacles pivotally mounted apart from each other on traction-wheels, with a piece inclined toward each of the receptacles and uniting 70 their upper inner portions, a cutter-bar horizontally located above the front portion of said receptacles, suitable gearing and connections uniting the cutter-bar and the shafts of the traction-wheels, substantially as 75 described.

3. The combination of two collecting-receptacles pivotally mounted apart from each other on traction-wheels, with a piece inclined toward each of the receptacles and uniting 80 their upper inner portions, a cutter-bar horizontally located above the front portion of said receptacles, suitable gearing and connections uniting the cutter-bar and the shafts of the traction-wheels, a lever fulcrumed on one of said receptacles and connection 85 between said lever and the poles of the machine for tilting the same, substantially as described.

4. The combination of two collecting-receptacles mounted apart from each other on traction wheels, with a piece inclined toward each of the receptacles and uniting their inner upper portions, a series of sprocket-wheels journaled above the front portion of said receptacles at each inner side thereof, a sprocket-chain carrying a number of fingers and engaging each of the series of sprocket-wheels, and means to drive the said chains by the rotation of the traction-wheels, substantially 95 as described.

5. The combination of two collecting-receptacles mounted apart from each other on traction-wheels, with a piece inclined toward each of the receptacles and uniting their inner portions, a series of sprocket-wheels journaled above the front portion of said receptacles at each inner side thereof, a sprocket-chain carrying a number of fingers and engaging each of the series of sprocket-wheels, means to 105 drive the said chains by the rotation of the traction-wheels, and a lever fulcrumed on one of the receptacles and connections uniting said lever and the poles of the machine for 110 tilting the same, substantially as described. 115
